UNITED STATES PATENT OFFICE.

HENRY W. MORGAN, OF ROCHESTER, NEW YORK.

NAILING-MACHINE.

1,140,605.

Specification of Letters Patent. Patented May 25, 1915.

Application filed March 5, 1914. Serial No. 822,554.

To all whom it may concern:

Be it known that I, HENRY W. MORGAN, of Rochester, in the county of Monroe and State of New York, have invented certain new and useful Improvements in Nailing Machines; and I do hereby declare the following to be a full, clear, and exact description of the same, reference being had to the accompanying drawings, forming a part of this specification, and to the reference numerals marked thereon.

My invention relates to nailing machines, and it has for its principal object to provide a mechanism that is especially adapted for 15 nailing together the parts of paper or paper board boxes, in a manner that will insure securely attaching the parts, without leaving any projecting or unprotected ends of the nails.

20 A further purpose of the invention is to afford a simple construction that can be manufactured at a minimum cost, and by which the operation can be readily and quickly effected.

25 To these and other ends the invention consists in certain improvements and combinations of parts all as will be hereinafter more fully described, the novel features being pointed out in the claims at the end 30 of the specification.

In the drawings: Figure 1 is a view in side elevation of a machine constructed in accordance with a preferred embodiment of 35 my invention, showing the boxes in position, and partly broken away to afford a view of the interior; Fig. 2 is a sectional view of one of the anvils, partly broken away, and illustrating the first step in driving the nails; Fig. 3 is a sectional view on the line 3^a—3^a of Fig. 2; Fig. 4 is a plan view of the anvil; Fig. 5 is a sectional view of the other anvil and its coöperating plunger, showing the final step 40 in securing a nail to the box; Fig. 6 is a perspective view of the body portion of a box of the character for which the present machine is designed; and Fig. 7 is a perspective view of the bottom wall before it 45 is attached to the body portion.

50 Similar reference characters throughout the several figures indicate the same parts.

The invention is susceptible of various applications and among other uses is designed especially for attaching together the walls 55 of boxes made of paper, paper board, fiber, fiber board, and the like, so that they may be

tightly secured, and whereby the entire operation can be very quickly accomplished. To this end, I have provided a mechanism in a unitary structure that enables the result 60 to be effected in two operations, the nails being driven into the walls of the box so that in the finished structure the ends of the nails will be entirely concealed and protected.

65 In the present embodiment A designates a portion of the main frame of the machine upon which are supported a pair of anvils B, B' arranged in juxtaposition to each other, these being mounted on holders C, C' 70 which are slidable upon the guides D and adjustable by means of the threaded posts E which coöperate with threaded openings in the holders.

75 The anvil B is provided in its working face with a plurality of nail deflecting recesses, the purpose of each of which is to engage the pointed end of the nail as it strikes the anvil and bend it laterally upon itself in the manner shown in Fig. 2. In 80 order that the nail may enter the recess more readily, and to insure proper deflection of the end portion, I construct each recess F so that it is widest at the nail receiving end, as designated at f, and tapered thence toward 85 the opposite end, the width of the recess at the narrower end being slightly greater than the thickness of the nail. The depth of the recess F is such that when the nails have 90 been driven home by the hammer, the extreme points are bent upwardly far enough to barely engage the adjacent face of the box as shown in Fig. 2. Arranged above the recesses F are the nailing chucks G which are supplied with nails in the usual manner in 95 this class of machinery, and H designate hammers, carried upon the cross-head I which may be reciprocated in any convenient manner.

100 J, J¹ designate a pair of boxes arranged upon the respective anvils, each embodying a body portion J² and a bottom portion J³ provided with flanges J⁴ which are adapted to engage the edges of the body portion, and to be attached by nails driven through the 105 several thicknesses on the four sides of the box. After the nails have been driven to the position shown in Fig. 2 by the first operation, it is desirable to drive the points of the nails upwardly within the walls of the 110 box and to flatten the lower part of the nails against the adjacent wall of the box. This

function is accomplished by the anvil B¹ upon which the box can be quickly positioned for the second operation after its removal from the anvil B. Coöperating with the anvil B¹ is a plunger K which may be reciprocated in any convenient manner, and for this purpose is preferably carried by the aforementioned cross-head I. Upon placing the box upon the anvil B¹ with the nails in the position shown in Fig. 2, and lowering the plunger K until it comes into operative relation with the anvil, the nails are clenched, causing the ends to be forced upwardly into the walls of the box, and flattening the lower portion against the adjacent wall of the box as shown in Fig. 5.

By arranging the anvils in juxtaposition to each other, I provide an economical and simple method for driving and clenching the nails by two operations, all that is required being to shift the box from one position to the other, and this can be accomplished expeditiously with the means that I have described. The parts of the box are secured together in a most efficient manner, enabling the production of a finished article that possesses sufficient strength for all required purposes and can be manufactured at a low cost.

I claim as my invention:

1. In a nailing machine, the combination with a main frame, of a pair of anvils supported on said frame in juxtaposition to each other, nailing chucks arranged above one of said anvils, a reciprocating cross-head mounted on the frame, a series of hammers

carried by the cross-head and coöperating with said chucks, and a plunger also carried by the cross-head and coöperating with the other anvil.

2. In a nailing machine, the combination with a main frame, of a pair of anvils supported on said frame in juxtaposition to each other, nailing chucks arranged above one of the anvils, reciprocating hammers coöperating with said chucks, and a reciprocating plunger coöperating with the other anvil.

3. In a nailing machine, the combination with a main frame, of a pair of anvils supported on said frame in juxtaposition to each other, one of the anvils having a plurality of nail deflecting recesses in its working face, nailing chucks arranged above said recesses, hammers coöperating with said chucks, and a reciprocating plunger coöperating with the other anvil.

4. In a nailing machine, the combination with a main frame, of a pair of anvils supported on said frame in juxtaposition to each other, one of the anvils having a plurality of nail deflecting recesses which are widest at their receiving ends and tapered from their receiving ends toward their opposite ends, chucks arranged above said recesses, hammers coöperating with said chucks, and a reciprocating plunger coöperating with the other anvil.

HENRY W. MORGAN.
